UNITED STATES PATENT OFFICE.

HERMAN C. HIRSCHY, OF MINNEAPOLIS, MINNESOTA.

WRINGER.

1,399,482.

Specification of Letters Patent.

Patented Dec. 6, 1921.

Application filed March 1, 1920. Serial No. 362,319.

To all whom it may concern:

Be it known that I, HERMAN C. HIRSCHY, a citizen of the United States, residing at Minneapolis, county of Hennepin, State of Minnesota, have invented certain new and useful Improvements in Wringers, of which the following is a specification.

In the operation of a clothes wringer, provision is made for quick release of the action 10 of one wringer roll upon the other to avoid injury to the fingers or hand of the operator and to enable the operator to withdraw any article from between the rolls during the wringing operation. Generally in these 15 wringer roll releasing devices the lower roll is positively driven and continues its operation when the rolls have been separated and it is desirable to positively stop revolution of the lower roll when the wringing operation 20 ceases.

The object of my invention is to provide a driving means which, when the rolls are separated, will be automatically disconnected from both rolls and will remain so 25 disconnected until the two rolls are again adjusted in their working position.

The invention consists generally in various constructions and combinations, all as hereinafter described and particularly pointed 30 ed out in the claims.

In the accompanying drawings forming part of this specification,

Figure 1 is a longitudinal sectional view through the wringer embodying my invention,

Fig. 2 is a longitudinal sectional view showing the relative position of the rolls when the release device has been operated,

Fig. 3 is a transverse sectional view on the line 3—3 of Fig. 1,

Fig. 4 is a transverse sectional view on the line 4—4 of Fig. 2.

In the drawing, 2 represents the metallic frame of the wringer. 3 is a housing for 45 the upper end of the drive shaft 4 on which a beveled pinion 5 is mounted meshing with a gear 6 on a short shaft 7 that is journaled in bearings 8. A pinion 9 is mounted on the end of the shaft 8 meshing with a similar 50 pinion 10 on an extension of the shaft 11 of the upper roll 12. This shaft has a ball bearing 13 in a box 14 in the wall of the housing 15 which incloses the gear 10. A pinion 17 is mounted on the shaft 11 adjacent one end of the roll 12 and a similar

pinion 17^a is mounted on the shaft at the other end of the roll in a housing 21. A lower roll 18 has a shaft 19 journaled in a housing 2^b of the frame 2 in ball bearings 19^a, and this shaft is provided with a pinion 20 which meshes with the pinion 17 of the shaft 11. At the opposite end of the roll 18 is a pinion 20^a which meshes with the pinion 17^a and is inclosed in a housing 21^b. The housings 15 and 21 are pivoted at 23 to 65 the housings 2^b and 21^b and allow the upper roll to be lifted away from the lower roll, said pivots 23 being located on one side of the lower roll and studs 24 being mounted in the frame of the wringer on the other side 70 of the roll and limited against upward movement by a helical spring 25 and provided with lugs 26 which bear on the frame and prevent downward movement of the studs.

The housing 21^a which extends over the 75 upper roll is provided with a hand grip 27 and is pivoted to the housings 15 and 21 by pins 28 which are mounted on the housings to engage the recessed upper ends of the studs 24 and lock the upper and lower rolls 80 in their working position but allowing the rolls to separate under pressure of the clothes passing between them, the springs 25 yielding for this purpose. This release device is already covered by U. S. Letters 85 Patent and I make no claim to the same herein.

It will be noted that the drive from the shaft 4, instead of being direct to the shaft 19 of the lower roll, is carried up around and 90 through the shaft 11 of the upper roll and from this it must follow that when the gears 9 and 10 are separated and by the release of the upper roll from the lower one that the drive to the lower roll will be positively 95 broken and cannot be resumed again until the upper roll is returned to its working position. In this way I am able to positively check further revolution of the lower roll as soon as the release is operated to 100 separate the two rolls.

An important point in the construction, resulting from the stopping of both rolls, is the complete relief to the motor of the load. In constructions wherein the lower roll is 105 continuously driven it often happens that the clothes will be wound on this lower roll, resulting in such load that the motor will be stalled or burned out. In the improved device there is an absolute relief of the load as 110

soon as the rolls are separated and, consequently, there is positively no danger of overloading or burning out the motor.

I claim as my invention:

- 5 1. A clothes wringer comprising a frame having a normally fixed section and a movable section hinged thereto, a roll journaled in said fixed section, a roll journaled in said movable section and adapted to be moved with said movable section to a non-working position with respect to said fixed section roll, mechanism spaced from the fixed section roll for normally driving both rolls through the shaft of the movable section 10 roll and being rendered inactive for driving either roll upon movement of said movable section and its roll from said fixed section roll.
- 15 2. A clothes wringer comprising a frame having a fixed and a movable section, a lower wringer roll journaled in said fixed section, an upper wringer roll mounted in said movable section, said rolls having meshing pinions for normally driving one roll from the other, a stationary driving shaft 20 geared to the shaft of the roll that is mounted in said movable section for driving said lower roll through the shaft of the upper roll and said driving shaft becoming inoperative for driving both rolls when said upper roll and its support are moved out of working position with respect to said lower roll and its section.
- 25 3. A clothes wringer comprising a metal frame having a fixed portion and a hinged upper portion, a lower wringer roll journaled in said fixed portion, an upper wringer roll mounted in said hinged portion and adapted to swing toward and from said lower roll, said rolls having meshing pinions 30 for driving one roll from the other, and a shaft in axial alignment with and spaced relation to the shaft of said lower roll and geared to the shaft of the upper roll for driving said lower roll through the shaft 35 of said upper roll.
- 40 4. A clothes wringer comprising a frame having a fixed and a hinged section, a lower wringer roll mounted in said fixed section, an upper wringer roll mounted in said hinged section, said rolls having meshing pinions for driving one roll from the other and said pinions becoming separated when said upper roll is moved away from said lower roll, a drive shaft having a driving 45 connection with the shaft of said upper roll

and through the shaft of said upper roll and said pinions with the shaft of the lower roll, the movement of said hinged section of the wringer frame away from said fixed section separating said rolls and said driving connection.

5. In combination, a wringer frame having separable sections, a roll journaled in each section, separable intermeshing pinions 60 normally connecting the two rolls, one roll having a gear fixed within its frame section to its shaft, and a drive member mounted in part in the companion frame section for meshing with the gear and separable therefrom upon separating the frame sections.

6. A clothes wringer comprising a frame, a lower wringer roll mounted therein, an upper wringer roll mounted for movement toward and from said lower roll, said rolls 75 having meshing pinions for driving one roll from the other and said pinions becoming separated when said upper roll is moved away from said lower roll, a drive shaft having a driving connection with the shaft 80 of said upper roll and through the shaft of the upper roll and said pinions with the shaft of the lower roll, the connection between said drive shaft and said upper roll becoming inoperative and stopping revolution of both rolls when the upper roll is moved out of driving engagement with the lower roll.

7. A clothes wringer comprising a frame having a normally fixed and a movable section and wringer rolls mounted therein respectively, said movable section and its roll being mounted for movement bodily away from said fixed section and its roll to an inoperative position, said rolls having meshing pinions for driving one roll from the other when they are in their normal working position, said pinions becoming separated when said movable section is moved to its non-working position, a drive shaft 90 operatively connected with the roll of said movable section for driving the roll of said fixed section through said movable section roll and said pinions, the separation of said pinions when said movable section is 95 moved to its non-working position disconnecting said drive shaft and stopping revolution of both rolls.

In witness whereof, I have hereunto set my hand this 25th day of February, 1920. 110

HERMAN C. HIRSCHY.
